UNITED STATES PATENT OFFICE

148,206

DESIGN FOR A HEATING RADIATOR

George W. Zimbelman, Signal Mountain, Tenn.

Application November 14, 1945, Serial No. 123,753

Term of patent 14 years

(Cl. D81—21)

To all whom it may concern:

Be it known that I, George W. Zimbelman, a citizen of the United States, residing at Signal Mountain, in the county of Hamilton and State of Tennessee, have invented a new, original, and ornamental Design for a Heating Radiator, of which the following is a specification, reference being had to the accompanying drawing, forming part thereof, in which:

Fig. 1 is a side elevational view of a heating radiator embodying my new design.

Fig. 2 is an end elevational view on a reduced scale and as observed from the right of Fig. 1.

Fig. 3 is a top plan view, and

Fig. 4 is a bottom plan view thereof.

I claim:

The ornamental design for a heating radiator, substantially as shown.

GEORGE W. ZIMBELMAN.
